UNITED STATES PATENT OFFICE

162,867

COMBINED SCREW DRIVER AND CAP

Irvin A. Olson, Anacortes, Wash.

Application May 8, 1950, Serial No. 9,802

Term of patent 14 years

(Cl. D93—4)

To all whom it may concern:

Be it known that I, Irvin A. Olson, a citizen of the United States, residing at Anacortes, in the county of Skagit and State of Washington, have invented a new, original, and ornamental Design for a Combined Screw Driver and Cap, of which the following is a specification, reference being had to the accompanying drawing, forming part thereof.

Figure 1 is a front elevational view of a combined screw driver and cap showing my new design;

Figure 2 is a side elevational view thereof, and Figure 3 is a bottom plan view of the same.

I claim:

The ornamental design for a combined screw driver and cap, as shown.

IRVIN A. OLSON,
